UNITED STATES PATENT OFFICE.

WILLIAM N. HUNTER, OF BLANCHESTER, OHIO.

STAPLE-FORMING MACHINE.

No. 861,518.

Specification of Letters Patent.

Patented July 30, 1907.

Application filed August 11, 1905; Serial No. 330.

To all whom it may concern:

Be it known that I, WILLIAM N. HUNTER, a citizen of the United States of America, residing at Blanchester, in the county of Clinton and State of Ohio, have 5 invented certain new and useful Improvements in Machines for Forming Staples, of which the following is a specification, reference being had therein to the accompanying drawings.

The invention relates to improvements in machines 10 for feeding and cutting wire to form staples, more particularly designed for use in connection with brush machines.

In the drawings, Figure 1 is a longitudinal section through a portion of the brush machine, to which my 15 improvements are applied. Fig. 2 is a transverse section thereof; Fig. 3 is a sectional perspective view of the wire severing mechanism; Fig. 4 is a sectional elevation thereof; Fig. 5 is a sectional elevation of a wire feeding mechanism; and Fig. 6 is a section in a plane 20 transverse to Fig. 1 through the wire feed.

The brush machine in connection with which my 25 stapling mechanism may be employed may be of any suitable construction and forms no part of my present invention, except as hereinafter set forth. In general, this machine comprises a bunch grabber and carrier having the coöperating members M, M', which are laterally reciprocated to transfer the bunch in position for engagement with the stapling mechanism. The 30 operating means for this mechanism is not illustrated and the parts are merely shown in one position to indicate their relation to the stapling mechanism.

Above the parts M, M' is arranged a rotary head G inclosed in a casing H, this head being revolved by a 35 rotary shaft C on which it is mounted. This head is provided with suitable cams, which will be herein- 40 after specifically described, for operating various parts of the mechanism, the arrangement being such that the staples are successively formed in a position above the parts M, M' and are then engaged with a bunch of 45 bristles held by said parts M, M' and subsequently driven downward into engagement with the brush head which is located on a shelf or work support L there- beneath.

The mechanism comprises means for feeding the 45 wire and for cutting said wire into the required lengths for the staples, and also for forming pointed ends thereon. The feeding mechanism comprises a pair of rolls or rotary feeding disks O, the former being provided with a projecting segment which intermitt- 50 ently coöperates with the other disk to feed the wire. These disks O are mounted upon shafts O², secured in bearings upon the casing H. At their upper ends they are connected together by gears O⁴ and are driven from the shaft C through the medium of bevel gears O⁵. 55 At their lower ends, the shafts O² engage with adjustable bearings O⁶ which are yieldingly separated from each

other by the spring O⁷ and upon opposite sides of said bearings are the adjusting screws O⁸ by means of which they may be adjusted in position to move the disks O in proper relation for feeding. These disks O are 60 grooved for the reception of the wire and are preferably knurled so as to form a better hold upon the wire.

From the feeding disks O the wire is passed horizontally into the cutter P. This consists of a block P' which has formed therein a recess containing a seg- 65 mental die with which the punch P² engages. The wire is fed transversely through the recess preferably by the guide P³ which directs the wire across the segmental die at one side of the center thereof and preferably with the outer edge of the wire substan- 70 tially tangent to the inner face of the segment of the recess. The wall of the segment on the side that the wire enters is cut away so that in the operation of the punch the wire will be sheared only upon the opposite side of the segment and this severing operation 75 will cause the cutting of the wire obliquely so as to produce oppositely sharpened ends. The movement of the punch will carry with it the end of the unsevered portion of the wire, but this movement is permitted without shearing or cutting out any portion of the wire 80 by reason of the recess in the wall of the segment. In the return movement of the punch the wire is bent back again so as to be in position for another feeding operation, this being effected by the follower P⁴, which is actuated in one direction by the spring P⁵. The move- 85 ment of this follower is limited by the stop pin P⁶ which engages the recess P⁷ in the block P'.

From the cutter P the wire passes into engagement with a staple forming mechanism which may be of any suitable construction, but preferably comprises a pair 90 of jaws Q which are pivotally attached to the vertical reciprocating bar Q'. This bar is actuated by a cam groove Q² in the rotary head G with which the roller Q³ on the bar Q' engages. The bar Q' is slidingly secured in the bar Q¹ which is provided with a T-shaped 95 head Q⁵ and is slidingly secured in bearings in the casing H. This bar Q¹ has attached to its lower end the punch Q⁶ which is adapted to coöperate with the jaws Q in the manner to be herein- 100 after set forth. The head Q⁵ is provided with a cam slot Q⁷ with which the crank roller Q⁸ on the head G engages. Thus in the rotation of the head G the bar Q¹ will be reciprocated through the actuation of the roller Q⁸ and during this reciprocating movement an independent movement will be imparted to the bar Q' through the medium of 105 the roller Q³ engaging the cam slot Q².

Pivotedly attached to the casing H is an anvil R. This is preferably in the form of a bell crank at the lower end of which is arranged a projecting lug R' forming the anvil proper. The outer arm R² of the bell 110 crank engages with the cam slot R³ in the head G through the medium of the roller R⁴. This cam slot is

so shaped that during the rotation of the head G the anvil R will be actuated to move the lug R' into the path of the jaws Q and retain it in that position for an interval, after which the bell crank is again actuated to withdraw said lug. The timing of the parts is such that during the feeding movement of the wire, the jaws Q and their actuating bar Q' will remain stationary. Furthermore, the jaws Q are held in close relation to each other by means of a punch cam e engaging their upper ends closing said jaws at their lower ends so as to permit the wire to be fed therein without danger of the end of the wire catching in between the jaws. When the wire has been fed the required distance movement will be imparted to the bell crank lever R carrying the lug or anvil R' upward and simultaneously the jaws Q are separated so as to permit said lug to press on said wire between the jaws. This will form a clamp for firmly holding the wire during the severing operation. In order that the severed portion of the wire may be held from accidental disengagement from the jaws, it is desirable that the anvil shall press against the wire with a uniform tension, this tension being just sufficient to clamp the wire without bending it. I have therefore provided the actuating connection for the anvil with a slight lost motion and have arranged a spring R⁶ which when the anvil is moved upward will yieldingly press the same against the wire in engagement with the jaws. As soon as this section is severed, movement is imparted to the bar Q' which will press the jaws downward and around the anvil lug R', thereby bending the severed section of the wire into staple form. The anvil R' is then withdrawn out of the path of the jaws and the latter will continue their downward movement until the staple is engaged with the bunch, which latter has been moved by the grabber mechanism previously described into the path of the staple. As soon as the staple has been engaged with the bunch, the jaws Q will be moved towards each other, so as to bend the ends of the staple together and around the bunch. This movement is effected preferably by a projecting lug e on the bar Q' which is adapted to pass between pins f on the jaws Q and acts as a cam to separate said jaws at their upper ends, thereby closing them together at their lower ends, and pinching the staple. Moreover, the movement of the jaws will cause them to tightly grab the bunch, holding the same in the recess g at the lower end of the jaws. Simultaneously the grabber actuating mechanism will be actuated to return the grabber, but before the bunch-holding jaw is moved, the needle M' will be returned sufficiently to disengage from the lower edge of the bunch and permit the latter to be carried by the jaws Q out of engagement with the jaw M.

After the movement just described the jaws Q will be carried downward by the movement of the bar Q' until they contact with the upper face of the brush block, which is located on the table L and is arranged by the operator with one of its apertures in alignment with the jaws Q. As soon as this point is reached, further movement of the jaws is arrested but the bar Q' will continue its movement carrying the punch Q⁶ downward between the jaws until its lower end contacts with the upper end of the staple. Before contacting with the staple, the cam e passes from engagement with the pins f on the jaws Q permitting the holding portions of the

jaws to move apart by the actuation of the spring d² so as to disengage from the staple and allow the latter to be forced by the punch Q⁶ downward in the aperture in the brush block.

During the continued movement of the punch in driving the staple downward and driving the same into the wood, the jaws Q remain stationary and also remain in this position during the initial upward movement of the punch, thereby operating as a presser foot which retains the block from being drawn upward by frictional engagement with the punch. As soon as the punch has been disengaged from the aperture in the brush head, the jaws Q will be again moved upward by the actuation of the bar Q' and the parts will be returned to their initial positions.

The punch P² is actuated in its operation by the lever S which is fulcrumed at S' on the casing H and has one arm S² extending into the path of the roller S³ on the rotary head G. The opposite arm of this lever is provided with a lug S⁴ which engages a slot in the head S⁵ upon the punch P². Thus in the rotation of the head G the lever S will be actuated to reciprocate the punch P² at the proper time and the return movement of said punch is effected by the spring S⁶. The engagement of the lug S⁴ with the slotted head S⁵ is such that the punch P² is permitted a rotary adjustment in the die, and thus the cutting of the wire will not always be effected by the same portion of the punch.

From the description above given, it will be apparent that my construction of stapling mechanism has certain advantages among which are; first, that the wire feeding mechanism is such as to permit of accurate adjustment so as to insure proper operation at all times and second, the wire cutting mechanism sharpens both ends of the staples without wasting any portion of the wire.

As illustrated in Figs. 3 and 4, the follower P⁴ is provided with a shoulder for engaging the wire and preventing displacement thereof during the severing operation.

What I claim as my invention is:

1. A wire feeding mechanism comprising a pair of adjacent rotary feeding disks, laterally movable bearings in which said disks are journaled, a spring between said bearings, and adjustable stops on opposite sides of said bearings whereby said disks may be accurately positioned in relation to each other to feed the wire.

2. A wire cutter comprising a cylindrical block or die, a cutting punch adapted for reciprocation in said die, and means for feeding the wire transversely through the cylindrical recess of the said die at one side of the center thereof, the wall of said die being cut away at the edge.

3. The combination with means for intermittently feeding the wire, of a cylindrical cutter adapted to obliquely shear the wire, and means for straightening the portion of the wire deflected in shearing.

4. The combination with means for intermittently feeding the wire, of a cutter comprising a stationary and a movable member cooperating to obliquely shear the wire, the movable member deflecting the end of the unsevered portion of the wire, and means operating upon the return of said movable member for straightening the deflected end of the wire.

5. The combination with means for intermittently feeding the wire, of a cutter comprising a punch and die between which said wire is fed, one wall of said die being cut away to permit of lateral deflection of a portion of said wire, and a spring pressed follower for straightening said deflected portion upon the return of said punch.

6. The combination with means for intermittently feed-

ing the wire, of a cutter comprising a punch and die between which said wire is fed obliquely to the cutting edge of the die, the opposite wall of said die being cut away to permit of lateral deflection of the wire, and a spring-
5 pressed follower in said die adapted to straighten the deflected end of said wire upon the return movement of said punch.

7. A wire cutter comprising a cylindrical punch, a complementary die having a portion of its wall cut away, and means for projecting the wire between said punch and die to obliquely cross the periphery of the punch and also cross the cut-away portion of the die.

8. The combination with a punch and die, of means for feeding wire between said punch and die to cross a portion of the periphery thereof obliquely, a spring-pressed 15 follower in said die, against which the punch is pressed, and a shoulder on said follower for holding the wire from displacement.

In testimony whereof I affix my signature in presence of two witnesses.

WILLIAM N. HUNTER.
